UNITED STATES PATENT OFFICE.

GEORGE W. RUCKER AND EDWARD L. RUCKER, OF MINNEAPOLIS, MINNESOTA.

FLUE-CLEANER.

No. 894,538.

Specification of Letters Patent.

Patented July 28, 1908.

Application filed August 12, 1907. Serial No. 388,134.

To all whom it may concern:

Be it known that we, GEORGE W. RUCKER and EDWARD L. RUCKER, of Minneapolis, Hennepin county, Minnesota, have invented 5 certain new and useful Improvements in Flue-Cleaners, of which the following is a specification.

The object of our invention is to provide a flue cleaner in which the spiral or rotary action of the steam jet can be utilized for thoroughly cleaning the interior surfaces of the flues.

The invention consists generally in providing a flue cleaner head having a central 15 steam jet or nozzle and an opening around said nozzle through which air is drawn through the center of the flue.

Further, the invention consists in various 20 constructions and combinations, all as hereinafter described and particularly pointed out in the claims.

In the accompanying drawings forming part of this specification, Figure 1 is a sectional view of one end of a flue showing our 25 improved flue cleaner therein. Fig. 2 is a sectional view of a cleaner head. Fig. 3 is an end view, and Fig. 4 is a transverse sectional view.

In the drawing, 2 represents a flue, 3 the 30 flue sheet and 4 the steam supply pipe through which steam is admitted to the shank 5 of the cleaner head 6. This head consists of a disk like casting having a beveled end surface 7 and ports 8 in said surface 35 communicating with passages 9 which lead back through the head to the shank 5. The ports 8 are so arranged in the end of the head, as indicated in Fig. 3, that the jets of steam discharged therefrom will be directed 40 spirally against the surface of the flue as indicated by the arrows in Fig. 1.

The cleaner head has a central opening 10 with passages 11 on each side leading thereto and a pipe 12 is centrally arranged in the 45 opening 10 and has one end fitting into a wall 13 in the rear of the opening 10 and concentric with the shank 5 and the steam supply pipe 4. When steam is admitted through the pipe 4 it will rush into the pipe 50 12 and be discharged therefrom along the middle line of the flue. A portion of the steam will pass out through the passages 9 and the ports 8 and be directed thereby against the wall of the flue. The flowing of 55 the steam through the pipe 12 will create sufficient suction to draw in the air through

the openings 11 and form an air shaft centrally in the flue and within the spiral formed by the jets of steam discharged through the ports 8. This air shaft will have 60 the effect of holding the spiral jets of steam outwardly against the flue surface and hastening their passage through the flue, thereby shortening to a considerable degree the time required for cleaning a flue. We have 65 found from actual test that the introduction of this air shaft through the center of the flue will not only cause the jets of steam to more thoroughly clean the flue surface but will to a very marked extent hasten the passage of 70 the steam jets through the flue. In other words the shaft of air seems to have the effect of drawing the steam spirals after it through the flue from one end to the other where generally the steam spirals are held back or 75 cushioned by the pressure of the air in front of them. All this objection to the spiral jets as employed in flue cleaners of the ordinary type we have avoided by the introduction of 80 this large air shaft directly through the center of the flue. The head will be made in different sizes to fit different flues and the ports in the periphery of the head and the suction nozzle can be varied in size according to the pressure of the steam.

85 We claim as our invention:

1. A flue cleaner comprising a head having a shank for attachment to a steam supply pipe, laterally extending nozzles provided in said head and communicating with said shank, said passages terminating in ports through which the steam passes and is directed spirally against the wall of the flue, a tube centrally mounted in said head in line with said shank and forming a suction nozzle 90 and said head having an opening around said nozzle and through which opening air is drawn by the suction of the steam passing through said nozzle, the said air forming a shaft that is inclosed by the spirals from 95 said ports.

2. A flue cleaner comprising a head 6 having a hollow shank 5 for attachment to a steam supply pipe, said head being provided with a beveled surface 7 at its forward end 105 and laterally extending passages communicating with said shank and having ports 8 in said beveled surface, said ports being arranged to direct the steam spiral against the inner surface of the flue and said head having 110 a central opening 10 and air passages 11 and a tube 12 centrally arranged with respect to

said head and having its rear end mounted in the inner wall of the passages 9 in line substantially with the axis of said shank and the forward end of said pipe terminating at the forward end of said head and forming a nozzle through which the steam is directed centrally through the flue and whereby a suction will be formed and a shaft of air drawn through the passages 11 and through

the center of the flue, substantially as described. 10

In witness whereof, we have hereunto set our hands this 31st day of July 1907.

GEORGE W. RUCKER.
EDWARD L. RUCKER.
